UNITED STATES PATENT OFFICE.

WILLIAM W. LOWREY, OF STATEN ISLAND, NEW YORK.

DESIGN FOR A GLASS STOPPER FOR BOTTLES.

SPECIFICATION forming part of Design No. 24,447, dated July 2, 1895.

Application filed April 22, 1895. Serial No. 546,794. Term of patent 3½ years.

To all whom it may concern:

Be it known that I, WILLIAM W. LOWREY, a citizen of the United States of America, and a resident of Staten Island, Richmond county, 5 State of New York, have invented a new and useful Design for Glass Stoppers for Bottles, of which the following is a specification.

In the drawings, Figure 1 represents a front elevation of a glass stopper, showing my design. Fig. 2 represents a side elevation of same.

The leading feature of my design consists of a convexo-convex head having its greater periphery formed by angles terminating into 15 facets on the flat sides of the head, the extreme upper and central facet having its outer edge formed by an arc of a circle, the head terminating in a shank and stopper. The contour of the head, when viewed from the front, will resemble an irregular polygon, excepting the extreme upper and central facets, whose outer edge is joined by an arc of a circle, as aforesaid, and when viewed from its side or edge will present a spear-shaped 20 polygon. The contour of the head, when viewed from the front, resembles an irregular polygon, excepting the extreme upper and central facets, whose extreme outer line forms an arc of a circle. The continuity of the latter would, if carried out, make tangential contact with each of the points forming a part of the contour of the said head, excepting, of course, the lower right and left hand corners, the latter of which forms a part of the base- 25 line of the head aforesaid, shank or neck, which in turn is integral with the stopper.

The head of the stopper, when viewed from its side or edge, will present an oblong shape. The contour thereof is also formed by the plane surfaces of the facets, thereby giving 40 it the appearance of an irregular-shaped polygon.

A is the convexo-convex head, having its entire surface formed by facets *b*, the extreme outer facets *c* forming, as they do, the 45 polygonal-shaped contour. The upper and central facet *d* has its extreme outer edge formed by an arc of a circle.

The base-line of the head *A* terminates in a hexagonal-shaped shank or neck *f*, the latter of which is integral with the stopper *g*.

It will be obvious that the head *A*, being of a convexo-convex shape, will naturally form an edge, as shown at *h*, Fig. 2. It will also be obvious that with this shaped head 55 and the manner in which the facets forming the surface thereof are grouped when viewed from the front will present a spheroidal-shaped figure, whose prismatic effects produce an object of great brilliancy.

60

What I claim is—

The design for a glass stopper for bottles herein shown and described.

In testimony that I claim the foregoing as my invention I have signed my name, in presence of two witnesses, this 15th day of April, 1895.

WILLIAM W. LOWREY.
